UNITED STATES PATENT OFFICE.

JAMES C. WOODSON, OF MANSFIELD, OHIO, ASSIGNOR TO WESTINGHOUSE ELECTRIC & MANUFACTURING COMPANY, A CORPORATION OF PENNSYLVANIA.

ELECTRIC FURNACE.

Application filed January 19, 1927. Serial No. 162,013.

My invention relates to electric arc furnaces and has for its object the provision of means for regulating the consumption of current in such furnaces.

5 In practicing my invention, I provide a furnace wherein a plurality of plural electrode heads are symmetrically arranged on the top thereof. The electrodes in each head are of the "repel arc" type and are 10 pivotally mounted and weighted to normally bring the ends thereof into engaging relation, the arrangement being such that upon the establishment of a circuit through said electrodes a magnetic field is formed 15 which swings them apart to establish an arc therebetween. Arc furnaces of this type are well-known in the art and are shown more particularly in U. S. Patent No. 1,352,541 to Von Schlegell issued Sept. 14, 1920. 20 The arrangement of the electrode heads is such that one electrode in each head is adjacent to a single electrode of each of the other heads, and selective means are provided to weight these adjacent electrodes to 25 swing them in an opposite direction.

Switches and suitable reactances are provided in the circuits of all of the electrodes to selectively energize them.

In the accompanying drawings, 30 Fig. 1 is a plan view of an electric furnace embodying my invention;

Fig. 2 is a section in elevation, taken on the line II-II of Fig. 1; and

Fig. 3 is a diagrammatic showing of the 35 circuit connections.

An electric arc furnace designated broadly as 1 and comprising a suitable refractory lining 2 and enclosing a furnace chamber 3, is provided with three electrode heads 4 mounted in the top of the furnace and symmetrically arranged both peripherally and radially with respect to the center thereof. In each of these electrode heads there is mounted a heating unit comprising three 45 electrodes such as a', b' and c'. These electrodes are pivotally mounted by means of a collar 10 carrying depending knife edges 11. Sockets 13 are formed upon said collars 10 for receiving weight arms 14 upon 50 which weights 12 are adjustably mounted to cause the lower ends of each set of electrodes, such as a', b' and c' to normally engage, all of which is disclosed in the Von Schlegell patent. In general the weights 14

are so located as to extend away from the 55 central axis of each electrode head. The electrodes a'', b', and c'' of the three electrode heads respectively, are positioned adjacent to the center of the top of the furnace at equal distances therefrom. These 60 three electrodes are provided with additional sockets 13' on the collars 10 thereof diametrically opposite to the sockets 13 so that the weight members 12, 14 may be inserted 65 therein to bias the ends of these electrodes in an opposite direction. Because of the position of these three electrodes adjacent to the center of the top of the furnace and symmetrically spaced peripherally thereof, this movement brings the ends 70 thereof into engaging relation.

Each of the electrodes a', a'' and a''' is 75 electrically connected to phase a of a three phase supply line as shown in Fig. 3, through suitable switch means and reactances, as indicated at 16 in Fig. 3. Likewise electrodes b', b'' and b''' and electrodes c', c'' and c''' are connected to phases b and c respectively.

In the normal operation of the devices 80 with all of the switches closed, each of the electrode heads constitutes a separate heating element all of which are symmetrically arranged in the furnace top and are connected to the supply line for parallel but independent operation. If it is desired, however, to decrease the consumption of power, 85 all of the switches are opened except those in the circuits of the three electrodes a''', b' and c'', weights and weight arms 12-14 are then inserted into the sockets 13' of the respective collar 10 and causes these electrodes to swing into operating relation to form a 90 separate heating element at the center of the furnace.

Various modifications may be made in the 95 device embodying my invention without departing from the spirit and scope thereof, and I desire that only such limitations shall be placed thereon as are imposed by the prior art or are specifically set forth in the 100 appended claims.

I claim as my invention:

1. In an electric arc furnace, a plurality 105 of heating units comprising electrodes mounted in operative relation, means for electrically connecting said units for parallel operation, and means forming a separate heating unit composed of a single electrode

from each of the first mentioned heating units.

2. In an electric furnace of the repel arc type, a plurality of groups of cooperating electrodes mounted in said furnace, means for electrically connecting said groups for parallel operation, means for selectively cutting out of circuit all but one of the electrodes of each group, and means for operating the 10 remaining electrodes as a separate group.

3. In an electric arc furnace, a plurality of heating units mounted in the roof of said furnace, each of said units comprising a plurality of pivoted electrodes normally biased 15 into cooperating relation, and selective means for biasing one electrode in each group into contacting relation with one electrode of each of the other groups to form a separate heating unit.

20 4. In an electric furnace, three heating units mounted in the roof of said furnace equidistant from the center thereof and from each other, said heating units each comprising pivoted electrodes weighted to

normally swing the ends thereof into cooperating relation, selective means to weight certain of said electrodes to swing in an opposite direction, said last named electrodes being so positioned that upon movement in said opposite direction the ends thereof are 25 brought into cooperating relation to form a separate heating unit.

5. In an electric arc furnace, a plurality of heating units mounted in the roof thereof and comprising pivotally mounted electrodes 35 weighted to bring the ends thereof into cooperating relation, and selective means associated with one electrode of each unit for weighting them to swing the ends thereof in a different direction, said electrodes being so 40 arranged that when swung in said different direction the ends thereof cooperate in operative relation.

In testimony whereof, I have hereunto subscribed my name this 11 day of January, 1927.

JAMES C. WOODSON.
